UNITED STATES PATENT OFFICE.

ROBERT S. GRAHAM, OF NEW YORK, N. Y.

KEY FOR TYPE-WRITING AND OTHER MACHINES.

1,084,005.

Specification of Letters Patent. Patented Jan. 13, 1914.

Application filed February 7, 1913. Serial No. 746,795.

To all whom it may concern:

Be it known that I, ROBERT S. GRAHAM, a citizen of the United States, and resident of the borough of Manhattan, in the city and State of New York, have invented a new and useful Improvement in Keys for Type-Writing and other Machines, of which the following is a specification.

My invention relates to keys for type-writing and other machines, and has for its object to provide a key having separate character bearing and finger engaging surfaces so that when the finger is resting upon the key, the character will still be exposed to view.

Practical embodiments of the invention are represented in the accompanying drawings, in which—

Figure 1 represents one embodiment in top plan; Fig. 2 represents a front view of the same, and Fig. 3 represents a section taken in the plane of the line C—C of Fig. 2. Fig. 4 represents a top plan view of another embodiment of my invention; Fig. 5 represents a view in front elevation of the same, and Fig. 6 represents a section taken in the plane of the line D—D of Fig. 5.

In both the embodiments shown, the key is provided with separate character bearing and finger engaging surfaces.

In the form shown in Figs. 1, 2 and 3, the key stem is denoted by 1 and the key head by 2. This key head 2 is provided with a finger engaging surface 7 and a ring 10 embraces the key head, which ring is provided with a downwardly and forwardly extended tab 11 having its outer surface arranged to bear the character. This ring 10 and tab 11 may be permanently or removable applied to the key head 2, as desired.

The key head is shown as oval in form so as to bring the character bearing surface within the periphery of a key of ordinary round form.

In the form shown in Figs. 4, 5 and 6, the key head 2 is provided with a cushion piece 12, having a finger engaging surface 13, an air space 14 being formed between

the top of the key head 2 and the top of the cushion piece 12. This cushion piece is provided with a flange 15 which fits over the key head 2, and the ring 10 in this instance embraces the flange 15.

The above described embodiments are only a few of the many different forms in which my invention could be embodied.

By the use of my invention it will be seen that the character will not be obliterated by the extended use of the key, and it will furthermore be seen that the cushion piece may be readily applied to the key head without disturbing the character bearing surface thereof.

It is evident that various changes might be resorted to in the construction, form and arrangement of the several parts without departing from the spirit and scope of my invention; hence I do not wish to limit myself strictly to the structure herein shown and described, but

What I claim is:

1. A key having a finger engaging surface and a ring embracing the key head having a character bearing surface.
2. A key having a finger engaging surface and a ring embracing the key head having a character bearing tab projecting therefrom.
3. A key comprising a head, a cushion piece having a finger engaging surface and a ring embracing said cushion piece having a character bearing surface.
4. A key comprising a head, a cushion piece having a finger engaging surface and a ring embracing said cushion piece and having a character bearing tab projecting therefrom.

In testimony that I claim the foregoing as my invention, I have signed my name in presence of two witnesses, this fifth day of February, 1913.

ROBERT S. GRAHAM.

Witnesses:

F. GEORGE BARRY,
HENRY C. THIEME.
